UNITED STATES PATENT OFFICE.

JOHN BACHUS, OF JERSEY CITY, NEW JERSEY.

ADJUSTABLE DOOR-FRAME.

SPECIFICATION forming part of Letters Patent No. 680,015, dated August 6, 1901.

Application filed March 28, 1901. Serial No. 53,214. (No model.)

To all whom it may concern:

Be it known that I, JOHN BACHUS, a citizen of the United States, and a resident of Jersey City, in the county of Hudson and State of New

5 Jersey, have invented a new and Improved Adjustable Door-Frame, of which the following is a full, clear, and exact description.

The invention relates to carpentry; and its object is to provide a new and improved adjustable door-frame arranged to permit convenient and ready adjustment of the rabbet-strip at any time to insure proper opening and closing of the door without requiring planing or rehanging of the door, as has been 10 so frequently practiced heretofore, to overcome the defects caused by swelling, shrinking, settling, or warping of the door-frame or the door, or both.

The invention consists of novel features and 20 parts and combinations of the same, as will be fully described hereinafter and then pointed out in the claims.

A practical embodiment of the invention is represented in the accompanying drawings, 25 forming a part of this specification, in which similar characters of reference indicate corresponding parts in all the views.

Figure 1 is a sectional plan view of the improvement. Fig. 2 is a like view of the same 30 previous to the adjustment of the rabbet-strip, the section of the trimming-board being removed to give access to the adjusting device for the rabbet-strip. Fig. 3 is a front elevation of the improvement. Fig. 4 is a side elevation of the same. Fig. 5 is a sectional plan view of a modified form of the improvement, and Fig. 6 is a perspective view of the side of the head-jamb in a separated position.

40 On the stud A of the door-frame are secured the usual laths and plaster B, and the door-jamb C, forming, with the removable section D' of the door-trimming D, a guideway E, in which is adjustably held a rabbet-strip F, 45 having a door-stop F', either integrally formed therewith or separately secured thereto. By adjusting the rabbet-strip F in the guideway E toward or from the door G it is evident that a proper fit can be obtained at any time between the said rabbet-strip and the door G to insure proper opening and closing of the door at all times. The rabbet-strip F is held

in position on the stud A by screws H, two, three, or more in number, preferably formed with countersunk heads, according to the 55 character of the door-frame and its door.

In order to adjust the rabbet-strip F for the purpose, lag-screws I are employed screwing in the stud A, the heads I' of which screws abut either directly on the inner face of the 60 rabbet-strip F or against a metallic wear-plate J, secured to the inner face of the said rabbet-strip. Usually two such lag-screws I are employed and arranged diagonally on opposite sides of the corresponding fastening- 65 screw H, as is plainly indicated in Fig. 4, it being understood that when the section D' of the door-trimming B is removed by the carpenter then access is had to the inner portion of the guideway E and to the lag-screws 70 I, so that the same can be readily turned by the application of a suitable wrench on the heads I' of the screws to screw the same inward or outward in the stud A, and thereby adjust the rabbet F correspondingly from 75 or toward the door. Previous to making the desired adjustment the screws H are loosened, and after the desired adjustment has been made then the screws H are again screwed up so as to bring the inner face of the wear- 80 plate J in firm contact with the heads of the lag-screws I to securely hold the rabbet-strip F in position and in proper position relatively to the door G. (See for comparison Figs. 1 and 2.)

As shown in Fig. 5, the jamb C' forms with the rabbet-strip F' a door-stop for the door to abut against when closed, said rabbet-strip being adjustably held in the guideway formed between the jamb C' and the removable section D' of the door-trimming D', and lag-screws I' are employed by adjusting the said rabbet-strip the same as above described in reference to Figs. 1 and 2. Screws H' and H' serve to securely hold the rabbet-strip in 95 place on the stud A' and the jamb C' after adjustment is made.

In order to permit convenient moving of the rabbet-strip without forming an open joint between the rabbet-strip and the upper door-jamb, I prefer to make a groove-and-tongue connection between the said rabbet-strip and the head door-jamb F', as is plainly indicated in Fig. 6.

It will be seen that in my invention the jamb C is cut away on one side and forms in connection with the detachable section D' of the trimming a guideway for the rabbet-5 strip and also a housing for the lag-screws, to which access may be had by removing the detachable trimming-section D' without mar-10 ring the plaster-line. These lag-screws form the back bearing for the rabbet-strip to sol-15 idly rest against, and with the screws H permit the rabbet-strip to be rectilinearly and integrally adjusted.

A distinct and valuable feature of my in-15 vention is to be found in the fact that in the slamming of the door on the rabbet-strip F' the impact is not borne by the adjusting-20 screws, but comes against the stationary door-jamb C, which is firmly nailed in the usual way to the studding. This preserves the op-25 erative condition of the adjusting devices, avoids all rattling noise, and makes a solid and secure but adjustable rabbet-strip for the door.

Having thus fully described my invention, 25 I claim as new and desire to secure by Letters Patent—

1. A door-frame having the door-jamb cut away on one side to form a guideway between the door-jamb and the trimming-board, and 30 a rabbet-strip mounted in said guideway and integrally and rectilinearly adjustable toward and from the door, said rabbet-strip having throughout its adjustment a solid and direct abutment against the rigid portion of the door-jamb to resist the impact of the slamming of the door, as set forth.

2. A door-frame having a stud, a jamb secured thereto, but cut away on one side, a trimming-board forming with said jamb a guideway, a rabbet-strip mounted in said guideway, and means between said rabbet-strip and said stud, to integrally and rectilinearly adjust the rabbet-strip relatively to the door, said rabbet-strip having throughout 45 its adjustment a solid and direct abutment against the rigid portion of the door-jamb to resist the impact of the slamming of the door, as set forth.

3. A door-frame having a stud, a fixed jamb 50 cut away on one side, a trimming-board forming with the jamb a guideway, a rabbet-strip adjustably held in said guideway, means for integrally and rectilinearly adjusting the rab-

bet-strip toward or from the door, said means consisting of lag-screws seated in the stud 55 and forming a back bearing for the rabbet-strip, and fastening-screws for holding the rabbet-strip in position on said stud, said rabbet-strip having throughout its adjustment a solid and direct abutment against the rigid 60 portion of the door-jamb to resist the impact of the slamming of the door, as set forth.

4. A door-frame having a stud, a fixed jamb cut away on one side, a trimming-board forming with the jamb a guideway, the trimming-board being made in sections, one of which is removable to give access to said guideway, a rabbet-strip adjustably held in said guideway, and means for adjusting the rabbet-strip toward or from the door, said means comprising 65 lag-screws screwing in the stud and abutting with their heads against the inner face of the rabbet-strip to form a back bearing for the same and fastening-screws extending through the rabbet-strip into the stud, said rabbet-strip having throughout its adjustment a solid and direct abutment against the rigid portion of the door-jamb to resist the impact of the slamming of the door, as set forth.

5. A door-frame having a stud, a fixed jamb cut away on one side, a trimming-board forming with the jamb a guideway, the trimming-board being made in sections, one of which is removable to give access to said guideway, 85 a rabbet-strip adjustably held in said guideway, and means for integrally and rectilinearly adjusting the rabbet-strip toward or from the door, said means comprising lag-screws screwing in the stud, wear-plates on 90 the rabbet-strip and against which abut the heads of said lag-screws and fastening-screws passing through the rabbet-strip into the stud, said rabbet-strip having throughout its adjustment a solid and direct abutment 95 against the rigid portion of the door-jamb to resist the impact of the slamming of the door, as set forth.

In testimony whereof I have signed my name to this specification in the presence of 100 two subscribing witnesses.

JOHN BACHUS.
